CASH REGISTER

Bernis M. Shipley, Dayton, Ohio, assignor to
The National Cash Register Company, Dayton,
Ohio, a corporation of Maryland

Application July 29, 1935, Serial No. 33,666

13 Claims. (Cl. 235—9)

This invention relates to cash registers and accounting machines of the type illustrated and described in Letters Patent of the United States No. 1,619,796, issued March 1, 1927, to Bernis M. Shipley, and more particularly to a new and novel form of divided key bank and differential mechanism associated therewith.

An object of this invention is to provide a differential mechanism associated with a divided bank of keys in which the construction is simplified by locating both latches in a common plane, a driver for which being provided with two driving shoulders. This construction requires less space in the machine than required in divided key banks known in the prior art and also simplifies the construction of the keys so that they may all be constructed alike, except for one key having a shorter shank than the others.

Another object of this invention is to so construct the single driver that all of the differentially movable members are returned to their normal position by said driver.

With these and incidental objects in view, the invention includes certain novel features of construction and combinations of parts, the essential elements of which are set forth in appended claims and a preferred form or embodiment of which is hereinafter described with reference to the drawing which accompanies and forms a part of this specification.

In said drawing:

Fig. 1 is a section through the machine, just to the right of the divided bank of keys, looking toward the left.

Fig. 2 is a detail side view of the upper latch carrying arm and its associated beam.

Fig. 3 is a detail rear view of a portion of the mechanism for returning the upper latch carrying arm to its normal position.

Fig. 4 is a detail side view of the lower latch carrying arm and the beam associated therewith.

Fig. 5 is a fragmentary top plan view of the upper latch, its carrying arm and the latch driver.

Fig. 6 is a top plan view of the differential latch carrying arms, the lower latch, the latch driver and shows the links actuated by the differentially movable beams associated with said arms.

General description

The idea of a divided key bank is not broadly new, as is illustrated and described in Letters Patent of the United States, No. 1,908,068, issued May 9, 1933, to Bernis M. Shipley.

Such divided key banks are usually provided for the purpose of increasing the compactness of

the machines by combining in one bank two different groups of keys, such as, for example, clerks' keys and transaction keys, which keys are ordinarily contained in two separate banks, one bank for each group. This necessitates the use of two differentially movable members with the divided key bank, one member cooperating with each group of keys. The clerks' keys and transaction keys, through the two differentially movable members cooperating therewith, control the selection of the proper clerks' and transaction totalizers, as well as set up the indicators and type carriers, corresponding to the keys depressed.

Furthermore, in such previous types of divided key banks, the two differentially movable members are arranged parallel with each other, and both are controlled by the lower ends of the shanks of the keys stopping and "breaking" a latch carried by each member. However, since both groups of keys are arranged in the same plane, and the movable members are arranged parallel with each other, it is necessary that the ends of the shanks of one group of keys have secured thereto a rectangular metal block to increase the width of the shanks sufficient so that when any of the keys in that group are depressed they will stop and "break" the latch of its associated movable member. The shanks of the keys in the other group, which do not have such metal blocks secured thereto, are of sufficient width so that when any key in the latter group is depressed it will stop and "break" the latch of its particular movable member. In other words, the keys of one group are differently constructed from the keys of the other group, in order that both groups of keys may cooperate simultaneously with the latches on the two parallelly arranged differentially movable members.

The differential mechanism associated with such types of divided key banks consists of a segment, the two differentially movable members, and the two latches carried thereby. The segment is of sufficient width to coact with both of the parallelly arranged latches. When the segment is rocked clockwise during an operation of the machine, a shoulder formed on the segment drives both latches clockwise until they are stopped by depressed keys in their respective groups, which "break" the latches and cause them to engage notches formed in two latch plates, one plate being associated with each group of keys, said notches in each plate corresponding to the positions of the different keys in its respective group.

There are also provided two stop pawls, one associated with each latch. These stop pawls are provided for disconnecting the latches, in the zero positions, of whichever one of the differentially movable members it is not desired to operate.

Each of the differentially movable members has associated therewith mechanism for selecting the proper totalizer, indicator and type carrier corresponding to the key depressed.

The present invention, however, provides a new and novel form of divided key bank and associated differential mechanism which are of much more simple construction than the divided key banks and associated mechanisms of the type above described. By such simple construction, applicant's invention not only permits of lower cost in manufacture but also requires a lesser amount of space in the machine, thereby permitting the machine to be built with more compactness.

Described in general terms, the present invention consists of a divided key bank containing two different groups of keys; viz., clerks' keys and transaction keys, all of which keys are constructed identically alike, except one of the transaction keys has a shorter shank than the other keys.

A pair of differentially movable members, through which the depressed keys select the proper totalizers, indicators and type carriers, is also provided, but in this instance the latches carried by such movable members are arranged in the same plane.

The differential mechanism consists of a driving segment, the pair of differentially movable members and the latches carried thereby. The latches cooperate with the peripheral edge of the driving segment, which, due to the latches being arranged in the same plane, is no wider than would be necessary to coat with a single latch. However, there are two shoulders, spaced apart, formed on the driving segment, each shoulder being adapted to drive one of the latches when the driving segment is rocked clockwise during an operation of the machine. Due to the arrangement of the latches, it is only necessary to provide one latch plate, which has notches formed therein corresponding to the positions of the various keys in both groups.

Only one stop pawl is provided, which pawl serves to stop the lower latch when no key in its associated group is depressed.

It is apparent from the above general description, that the present invention eliminates the need for differently constructed keys, a notched latch plate, a stop pawl, and a wide driving segment, all of which were essential in previous types of such mechanisms. This results in a simplified construction, lower manufacturing costs, and less space required by such mechanism in the machine, thereby permitting the machine to be built more compactly.

65

DETAILED DESCRIPTION

Divided key bank

This key bank contains two different groups of keys, namely, clerks' keys 40 and transaction keys 41 (Fig. 1). The clerks' keys 40 are marked with the letters "A", "B", "D" and "E", representing the various clerks operating the machine, while the transaction keys 41 bear indicia, namely, "Cash", "Rec. Acc.", "Charge" and "Pd. out",

indicating the different characters of the transactions.

The keys 40 and 41 are slidably mounted in a frame 42 supported on rods 43 and 44 carried by the machine side frames 45, only one of which is shown. The keys 40 and 41 are held in their outer or undepressed positions by springs 46 in the usual and well known manner. When the keys are depressed they are retained in their depressed positions by the usual form of detents, one detent for each group of keys, which are fully illustrated and described in the above mentioned Shipley patent, No. 1,619,796. All of the keys 40 and 41 are of like construction, except the "cash" key 41 associated with the transaction group has a shorter shank than the other keys, the purpose of which will be later described.

Differential mechanism

Depression of any of the clerks' keys 41 and transaction keys 42 controls the movement of a differential mechanism associated therewith to select the proper totalizers and set the type carriers and indicators corresponding to the keys depressed.

This differential mechanism comprises a latch driver 52 (Fig. 1) and two differentially movable arms 53 and 54, each of which is pivotally mounted on a hub 55 supported by two hangers 72 and 78 (Figs. 5 and 6) supported on rods 76 and 77 mounted in the machine side frames 45. The arm 54 is made up of two plates 47 and 48 (Fig. 5), which plates are separated by a spacer 49 at their free ends and by a lever 83, to be hereinafter described, at their other ends.

The arm 53 (Fig. 1) associated with the clerks' group of keys 41 carries, by means of an arm 56 and a bell crank 57, a latch 58 which is constantly held in contact with the peripheral edge of the driver 52 by a spring 59. Likewise, the arm 54 associated with the transaction group of keys 42 carries, by means of an arm 60 and a bell crank 61, a latch 62 which is constantly held in contact with the peripheral edge of the driver 52 by a spring 63.

Since the latches 58 and 62 lie in a common plane, the driver 52 is notched to form two shoulders 64 and 65, which engage the feet of the latches 58 and 62, respectively, to drive the arms 53 and 54.

To operate the common driver 52, there is provided a pair of cams 66 and 67, fast to a main drive shaft 68, which cooperate with rollers 69 and 70, respectively, carried by a Y-shaped lever 71 pivoted on the hanger 72. The lever 71 is connected to the driver 52 by a link 73. During each cycle of operation of the machine, the cams 66 and 67, through the lever 71 and link 73, rock the segment 52 first clockwise and then counter-clockwise to its normal position.

When the segment 52 is driven clockwise by the cams 66 and 67, the differentially movable arms 53 and 54 are carried with their latches 58 and 62, respectively, up to points where the forwardly extending arms of the bell cranks 57 and 61 contact the ends of the depressed clerk's key and transaction key. Such contact results in the disengagement or "breaking" of the latches 58 and 62 from the driver 52 and engagement of the forward ends of the latches 58 and 62 with the particular notches of a series of notches 74 formed in a plate 75, supported by the hanger 72, which are opposite the latches when they are disengaged.

Upon the return movement of the driver 52 to

its normal position, means is provided for returning the arms 53 and 54 to their normal positions. This means consists of a flange 80 (Figs. 1, 3, and 6) formed on the driver 52 which engages a stud 81 mounted in the arm 53; while the inside of the driver 52 coacts with a stud 82 mounted in the arm 54. Thus, when the driver 52 is rocked counter-clockwise to its normal position, the arms 53 and 54, through the means just described, are returned to their normal positions.

As is customary in such types of "divided banks", when no key is depressed in either the clerks' group or the transaction group, means is provided for controlling the movement of the differentially movable arms 53 and 54 so that they are moved to their blank positions. The blank position for the arm 53 is the position just beyond the uppermost key 49 in the clerks' group of keys. The blank position of the arm 54 corresponds to the zero position of an amount bank.

When no clerk's key 49 is depressed, the arm 53, through the shoulder 64 engaging the latch 58, is moved with the driver 52 in a clockwise direction its maximum extent of movement to 25 the blank position of the arm 53.

When no transaction key 41 is depressed, the forward end of a lever 83 (Figs. 1, 4, and 6) pivoted on the hub 55 and having a slot 79 at its opposite end through which projects a pin 30 84 carried by the forwardly extending arm of the bell crank 61, contacts a stop pawl 85 thereby "breaking" the latch 62 and engaging the forward end thereof with the notch 74 directly opposite the latch, thus retaining the arm 54 in its blank position.

The stop pawl 85 is fast to a short shaft 80 carried by the frame 42 and is normally held in its effective position by a spring 87. However, when any one of the transaction keys 41 is depressed, the pawl 85 is rocked counter-clockwise to its ineffective position in the usual and well known manner shown in the above mentioned Shipley Patent 1,619,796.

All of the keys 49 and 41 are constructed identically alike, except the "cash" key 41 in the transaction group, which key has a shorter shank than any of the other keys. The purpose of providing the "cash" key 41 with a short shank is to prevent the end thereof from interfering 50 with the forwardly extending arm of the bell crank 57 on the movable arm 53 when the latter is in its normal position, in which position it is shown in Fig. 1.

For the purpose of stopping the lever 83 when the "cash" key 41 is depressed, there is secured to the frame 42 a bracket 93 (Fig. 1) which is located in the path of travel of the lever 83. Therefore, depression of the "cash" key 41 serves only to rock the stop pawl 85 to its ineffective position, thereby permitting the lever 83 to move upwardly until stopped by the bracket 93, which "breaks" the latch 62 on the arm 54 in a position opposite the "cash" key 41.

The means by which the differentially movable arms 53 and 54 select the proper clerks and transaction totalizers, and set indicators and type carriers corresponding to the depressed keys, will now be described.

To each of the differentially movable arms 53 and 54 (Figs. 1, 2, 4, and 6) is pivoted the usual beams 94 and 95, the outer ends of which are bifurcated to receive the large headed studs 96 and 97 carried by links 98 and 99, respectively. To maintain the proper side spacing of these 75 parts, the bifurcated walls of the beams 94 and

95 are recessed to accommodate the large heads on the studs 96 and 97. An anti-friction roller 100 carried by the Y-shaped lever 71 cooperates with the beams 94 and 95 to adjust the mechanism just described in the well known manner. 5

The lower ends of the links 98 and 99, (Fig. 1) are pivoted to arms 101 and 102, respectively, provided for the purpose of adjusting the type carriers in the printing mechanism. At their upper ends the links 98 and 99 are pivoted to segments 103 and 104, respectively, provided for the purpose of adjusting indicators and selecting totalizers with which the present machine is provided. The printing mechanism, indicating mechanism and totalizer selecting mechanism 15 have not been shown in this application, as they are fully illustrated and described in the before mentioned Shipley Patent No. 1,619,796.

While the form of mechanism herein shown and described is admirably adapted to fulfill the 20 objects primarily stated, it is to be understood that it is not intended to confine the invention to the one form or embodiment herein disclosed, for it is susceptible of embodiment in various forms all coming within the scope of the claims 25 which follow.

What is claimed is:

1. In a machine of the class described, the combination of a single bank of keys; a plurality of latches arranged in the same plane and adapted 30 to cooperate with said keys; and a common driving member having formed thereon a plurality of shoulders adapted to drive said latches to differential positions as controlled by the keys.

2. In a machine of the class described, the 35 combination of a plurality of groups of keys arranged in a single bank and in the same plane; a plurality of differentially adjustable members associated with said groups of keys; a plurality of latches arranged in a single vertical plane and 40 cooperable with the groups of keys; and a driving member associated with said latches to drive the differentially adjustable members different distances under control of the plurality of groups of keys. 45

3. In a machine of the class described, the combination of two groups of keys arranged in the same plane and in a single bank; two latches in the same plane as the two groups of keys, one associated with each group of keys and 50 adapted to be controlled only by the associated group of keys; differentially adjustable members carrying said latches; and a driving member having formed thereon two shoulders in the same plane as the keys and latches, one for each 55 of said latches, said driving member being operable to drive said differentially adjustable members and said latches different distances under control of the respective groups of keys.

4. In a machine of the class described, the 60 combination of a plurality of groups of manipulative devices; a plurality of differentially adjustable members; a latch carried by each of said members to control the positioning of the same as determined by said groups of manipulative devices, each of said latches, when at rest, being spaced apart in the direction of travel of the latches; a single driving element cooperating with said latches to drive said members differentially in one direction under control of said 65 groups of devices; and means on each member adapted to co-operate with said driving element to return said members and their associated latches to their normal positions. 70

5. In a machine of the class described, the 75

- combination of a plurality of groups of manipulative devices; a plurality of differentially adjustable members arranged side by side; a latch carried by each of said members to control the 5 positioning of the same as determined by said groups of manipulative devices, said latches being arranged in a single plane and operable from different normal positions; a single driving element cooperating with said latches to drive 10 said members in one direction under control of said groups of devices; a projection on one member in the plane of and operated by said element to restore said one member to its normal position; a projection on another of said members out of the plane of said element; and means 15 on said element extending laterally therefrom into the plane of last mentioned projection to return the last mentioned member to its normal position.
- 20 6. In a machine of the class described, the combination of two groups of keys arranged in a single key bank and in a common plane; two differentially adjustable members arranged side by side; a single driving segment operable 25 through a fixed excursion of movement and having a plurality of driving surfaces along its edge; latch supporting means on each of said differentially adjustable members; a latch carried by each of said supporting means, each latch being 30 arranged in the plane of and cooperating with one of said driving surfaces on said single driving segment to be actuated thereby to move said differentially adjustable members in one direction different distances as determined by 35 the groups of keys, each latch being normally positioned opposite its driving surface; a stud projecting laterally from one of said differentially adjustable members and into the plane of said segment to be actuated thereby by the return movement of the segment to return said member to its normal position; a stud projecting from the other of said differentially adjustable members; and means integral with said segment and projecting into the path of the last 40 mentioned stud to return its associated member to its normal position upon return movement of the segment to its normal position.
7. In a machine of the class described, the combination of two groups of keys arranged in a common plane in a single bank; a driving element having two spaced driving surfaces thereon, one adjacent each group of keys; two latches, each of said latches normally coacting with one of said driving surfaces for operation thereby; 50 and two differential members controlled in their differential movements by the cooperation of the keys and the latches during the entire operation of the driving element.
- 55 8. In a machine of the class described, the combination of a plurality of groups of keys arranged in a single bank, a latch related to each group of keys, differentially operable means associated with each latch, and a member having a plurality of spaced driving surfaces for driving the latches, said latches being driven by said spaced driving surfaces so as to be simultaneously cooperable with their related groups of keys to control the setting of their associated differentially operable means. 5
9. In a machine of the class described, the combination of a row of keys comprising two groups of keys, a latch related to each group of keys, members controlled in their movement by said latches, and a driving means having a plurality of spaced driving surfaces for simultaneously driving each latch relatively to only its related group of keys. 10
10. In a machine of the class described, the combination of two latches always located in a single plane, control means for the latches, and a single member for driving both latches, said latches cooperating with the control means whereby they are simultaneously controllable to extents of movement independently of each other. 20
11. In a machine of the class described, the combination of a single row of keys comprising a plurality of groups of keys; a plurality of latches located in a single plane, each latch being related to a group of keys and normally occupying a position immediately adjacent its related group of keys; and means for simultaneously driving said latches relatively to their groups of keys for control thereby. 30
12. In a machine of the class described, two groups of keys arranged in a single row; two latches, one related to each group of keys; means operable through a fixed distance for driving said latches, said latches being cooperable with depressed keys of their related groups throughout their operation through the fixed distance to disengage the latches from the driving means; and means under control of the keys of one group for immediately disengaging the latch related to that group from the driving means 40 when no key in that group has been depressed, said other latch remaining in engagement with the driving means throughout the complete movement of said means when no key in its related group has been depressed. 45
13. In a machine of the class described, the combination of a single bank of keys; a plurality of latches always located in a single plane and cooperable with certain of the keys in said bank of keys; and a driving element having means thereon to drive said latches different distances 50 as controlled by the keys. 55
